G. W. CARY

VALVE SPRING COMPRESSOR

Filed Mar. 14, 1921

FIG. 1.

FIG. 2.

WITNESS:

C. C. West.

INVENTOR.

George W. Cary,

BY

Frank A. Cutler,

ATTORNEY.

UNITED STATES PATENT OFFICE.

GEORGE W. CARY, OF GREENFIELD, MASSACHUSETTS.

VALVE-SPRING COMPRESSOR.

Application filed March 14, 1921. Serial No. 452,151.

To all whom it may concern:

Be it known that I, GEORGE W. CARY, a citizen of the United States of America, and a resident of Greenfield, in the county of

5 Franklin and State of Massachusetts, have invented a new and useful Valve-Spring Compressor, of which the following is a specification.

10 My invention relates to improvements in devices or appliances, for use in connection with internal-combustion engines, to compress the valve springs so as to enable the pins which are employed to hold such springs under compression, to be inserted or removed, and consists essentially of an L-shaped shank having serrations in the outer edge of its upstanding part, and provided with a valve-engaging member at the free end of its horizontal part, a slide mounted 15 on said upstanding part and having a fork or equivalent member which extends over said horizontal part, a lever or handle provided with engaging means for any of the teeth formed by said serrations, and pivotal 20 connecting means between said slide and said handle, together with such other parts and members as may be necessary or desirable in order to render the device complete in every respect, all as hereinafter set forth.

25 This valve-spring compressor is especially designed for use in connection with so-called valve-in-head motors.

30 The primary object of my invention is to produce a very simple, inexpensive, compact, and convenient device of the character described above, which consists of few parts that may be easily and quickly assembled and separated, can be readily adjusted to adapt it for the compression of springs of 35 different lengths, and is strong and durable.

35 This compressor is very simple in operation as well as in construction, and, owing to the latter fact, the same when taken apart can be packed compactly for shipment, and 40 stored in a comparatively small space when not in use.

45 Other objects and advantages will appear in the course of the following description.

50 I attain the objects and secure the advantages of my invention by the means illustrated in the accompanying drawings, in which—

55 Figure 1 is a top plan of a valve-spring compressor which embodies a practical form of my invention, and, Fig. 2, a side elevation of said compressor, the movable parts

being shown in elevated or raised position or condition in full lines and partially depressed, as when the device is in the act of compressing a spring, in broken lines. 60

Similar reference characters designate similar parts throughout the several views.

The valve-spring compressor illustrated in the drawings comprises a vertical shank 1 and an extension 2 at the base of and at 65 right-angles to said shank and forming a part of or being integral with the same, said shank being deeply serrated, in the edge opposite to that from which said extension projects, to form a series of teeth 3, which 70 teeth are of considerable length and incline at a sharp angle from their inner ends downwardly and outwardly or forwardly, and said extension being provided at its outer, rear, or free end with a center post 4 for a 75 valve; a slide, the construction of which will presently be described, adapted to be mounted on said shank, said slide having a fork 6 that extends over said extension and said post, which latter is directly below the 80 space between the outer terminals of the arms of said fork; a lever or handle 7 provided with a pivot 8 to engage between any two of said teeth; and a pivotal connection between said slide and said handle, such 85 connection in the present example consisting of a pair of links 9.

The slide referred to in the preceding paragraph consists of short, front and rear bars 5 and 10, respectively, which are of the 90 same thickness as the shank 1, and in practice slide up and down on opposite longitudinal edges of shank, said bar 5 sliding past the teeth 3, and a pair of connecting plates or side pieces 11 which are riveted or otherwise secured at 12 to said bars; said side pieces extending across both sides of said shank and on to both sides of said bars. The fork 6 is an integral part of the rear 95 bar 10.

100 The handle 7 may be made in any suitable form, but is preferably bifurcated at one terminal, and provided at such terminal with the pivot or pin 8. The aforesaid bifurcated terminal is represented at 13, and the space between the arms of the same is sufficient in width, and in depth as well, to receive or accommodate any of the teeth 13, while the pin 8 is in engagement with such teeth, and to permit said pin to be engaged with any of the teeth and withdrawn from such engagement easily and quickly. 110

The rear terminals of the links 9 are pivoted at 14 to the slide, such pivot passing through the side pieces 11 and the bar 10 behind the shank 1, while the forward terminals of said links are pivoted at 15 to the handle 7, said last-named pivot passing through the bifurcated portion or portions 13 of said handle. Thus it is seen that there is a link 9 on each side of the shank 1, slide, 5 and handle 7, and that said slide is actuated up and down, through the medium of said links, when the pin 8 is in place between two of the teeth 3 and said handle is rocked and as it moves up and down with an oscillatory 10 or swinging motion on said pin.

The upper, pointed end of the pin 4 is designed to enter the center hole in a valve, while the fork 6 is designed to engage a washer or other member on the valve-stem 20 above the spring thereon.

In assembling the parts, after the different members of the slide have been connected or fastened together, and the links 9 have been pivotally connected with said slide and 25 with the handle 7, the slide is slipped on over the top of the shank 1, with the fork 6 extending rearwardly and the handle 7 in front. The device is now ready to be adjusted for use. Adjustment is effected by 30 moving the slide up or down on said shank, as and to whatever extent may be necessary in order to permit the pivot 8 to be engaged with the required tooth 3, that is to say, with the tooth that will locate the handle 7, the 35 latter then swinging from and being supported by the links 9, in a position to elevate the forward terminal of said handle somewhat above the horizontal plane in which the rear terminal or bifurcation 13 is located, and engaging said pivot with such tooth. After such adjustment of the parts, 40 the compressor is slipped into place with the post 4 beneath the valve the spring for which it is desired to remove, and with the 45 fork 6 above such spring or an intervening washer or other member, and then the handle 7 is grasped at the forward terminal and depressed while fulcruming on the pin 8, with the result that the slide, with said fork, 50 through the medium of the pivot 15, links 9, and pivot 14, is depressed and said spring correspondingly compressed.

The handle 7 at this time is moved from the full-line position to and through the 55 broken-line position shown in Fig. 2, and may be swung downwardly and rearwardly far enough to carry the central longitudinal plane common to the links 9 behind and below the pin 8, so that the handle and connected parts operated thereby are locked, 60 and remain locked until said handle is swung forwardly and upwardly to an extent which carries the aforesaid plane of the links 9 forward of and above said pin, so 65 that the parts are unlocked.

While the valve-spring is under compression, the pin which confines the same in place above the valve is taken out, thereby making it possible to remove said spring after taking away the compressor. Before 70 taking away the compressor it is necessary, of course, to swing the handle 7 upwardly and elevate the slide to an extent sufficient to release the spring. When it is desired to replace the spring, the compressor is employed to compress the same while the pin is inserted in the valve-stem, and then said spring is released to the restraint afforded by said pin, the operation of the compressor being the same in this as in the first case. 75 80

It has not been deemed necessary to encumber this application with illustrations of a valve and its spring, together with the other closely connected or associated parts and members, because the application and 85 operation of my compressor will be sufficiently well understood without such illustrations.

At 16—16 in Fig. 1 are represented two washers or collars on the pivot 15 between the sides of the handle 7 or of the bifurcation 13 thereof and the adjacent terminals of the links 9, to afford the necessary support and connection for said links at their 90 forward terminals. 95

Although more or less change in matters of shape, size, and other features of the compressor herein shown and described may be made without departing from the spirit of my invention or exceeding the scope of 100 what is claimed, I am aware that serrated bars, slides, and operating handles have been variously combined and used before for the purpose of compressing valve springs, and do not, therefore, seek to claim such a combination broadly. 105

What I do claim as my invention, and desire to secure by Letters Patent, is—

1. The combination, in a valve-spring compressor, with a serrated shank having 110 an angular extension which is provided with an engaging member for a valve, of a slide mounted on said shank and having a fork to engage a valve spring, an operating handle provided with a non-oscillatory engaging member to contact with said shank, connecting means between said handle and slide, whereby the handle may be moved independently of the slide, said engaging member being the only medium of direct 120 connection between the handle and shank, and capable of entering any of the serrations of the shank, and said connecting means being connected with said handle forward of said engaging member. 125

2. The combination, in a valve-spring compressor, with a shank having teeth formed on its front edge and a rearward extension at the base, such extension being provided with an engaging member for a 130

valve, of a slide mounted on said shank and having a fork adapted to engage a spring, a handle having a pivot adapted to engage any of said teeth, and links pivotally connected at one terminal to said slide, and at the other terminal with said handle between said pivot and the free terminal of said handle.

3. The combination, in a valve-spring 10 compressor, with a shank having teeth on its front edge and an angular extension at the base, said base being provided with means to engage a valve, of a slide consisting of bars to engage the front and rear 15 edges of said shank, one of said jaws having a member to engage a spring, and of side plates embracing the sides of said shank and secured at their terminals to said bars, a handle having a pivot adapted to engage 20 any of said teeth, and links having their upper or rear terminals pivotally connected with said slide and their lower or forward terminals pivotally connected with said handle.

4. The combination, in a valve-spring 25 compressor, with a shank serrated in the forward edge to form a series of teeth, and having an angular extension at the base, which extension is provided with an engaging member for a valve, of a slide consisting of front and back bars and side connecting plates, the former embracing the longitudinal edges and the latter embracing the sides of said shank, and said rear bar having a member adapted to engage a 30 valve spring, links pivotally connected at their upper or rear terminals with said plates and rear bar, a handle bifurcated at one end to receive said shank and provided with a pivot pin to engage any of said 35 teeth, the lower or forward terminals of said links being pivotally connected with said handle between said pivot and the free end of the handle.
